UNITED STATES PATENT OFFICE.

HOMER B. HULBERT, OF SPRINGFIELD, MASSACHUSETTS.

PIPE-ORGAN.

1,333,715.

Specification of Letters Patent. Patented Mar. 16, 1920.

Application filed May 15, 1917. Serial No. 168,642.

To all whom it may concern:

Be it known that I, HOMER B. HULBERT, a citizen of the United States of America, residing in Springfield, in the county of 5 Hampden and State of Massachusetts, have invented certain new and useful Improvements in Pipe-Organs, of which the following is a specification.

This invention relates to pipe organs. One 10 object of the invention is to provide a device or mechanism for automatically varying the length of the column of vibrating air in an organ pipe so that the pitch of the tone of the pipe may be gradually raised or lowered 15 in order to produce an effect similar to that which is technically called "portamento" on a violin; that is to say, the passage from one note to another in a continuous glide through all of the intervening tones. In 20 pipe organs, as now constructed, so far as I am aware, there are no devices which will automatically accomplish this very desirable result. A second object of this invention is to provide a device for automatically increasing or diminishing the loudness of the 25 tone in an organ pipe, irrespective of the loudness of the tone in any other pipe. A third object of the invention is to provide means for automatically energizing the 30 valve operating magnets of two adjacent pipes in order to prevent a break in the tone when one pipe ceases to act and the adjacent one begins.

Broadly, this invention comprises a slide 35 that is arranged on the outside of an organ pipe and adapted, by means of a suitable lever device, as for example, a bell-crank lever, to be moved up or down by electro-magnets, thus varying the length of the 40 column of vibrating air in the pipe and consequently varying the pitch of the tone, either up or down, at the will of the player. It is to be understood that a slide is placed 45 on each of the pipes. The electro-magnets are preferably, though not necessarily, arranged in an arc of a circle for mechanical convenience for operating the valve operating lever device which governs the movement of the slide on the pipe. A sufficient 50 number of these electro-magnets is provided in order to cause the slides on the pipes to be moved the required distance on the pipes in order to accomplish the desired result; that is to say, in order to lengthen

or shorten the column of air in the pipe so 55 as to produce a continuous and harmonious sound from one note to another.

The invention further comprises an electrical connection between the last slide-operating magnet of one pipe and the first 60 slide-operating magnet of an adjacent pipe so that the bell-crank lever of the second pipe may be ready to operate as soon as the bell-crank lever of the first pipe ceases to act, thus preventing a sudden break in sound between 65 one pipe and the next one. The invention further comprises electrical connections between the series of magnets and a series of circuit closing levers that are arranged adjacent to or below the usual key-board, or 70 manual, of the organ whereby the operator by sliding his finger along a flexible key-board can conveniently control the operation of the slides on the pipes, as desired. Means are further provided for supplying 75 compressed air in varying quantities or pressures from the wind chest of the organ to each of the pipes and simultaneously with the operation of the slides on the pipes. Also, means are provided for slightly 80 lengthening the column of vibrating air in a pipe when the operator exerts an increased pressure on the key which causes or allows more air to enter the pipe. This would tend to lower the pitch proportionately, but as 85 the entry of more air into the pipe would naturally tend to raise the pitch, this lengthening of the column of air just compensates in the opposite direction and the 90 pitch remains the same however loud the tone may be made by the introduction of more air into the pipe. Any further objects relating to the nature and purpose of this invention will be set forth in detail in the body of the specification and will be particularly pointed out in the claims. 95

Referring to the drawings:

Figure 1 is a diagrammatic view showing in outline two organ pipes giving successive notes of the scale, the means for electrically 100 controlling the flow of compressed air to the pipes, the electro-magnetic means for varying the position of the slide which controls the length of the column of vibrating air in the pipe, and the electrical connections between a series of manually operated levers and the electro-magnets, also the electrical connections between said levers and 105

the electro-magnetic devices which control the flow of compressed air from the wind chest to the pipes.

Fig. 2 is a plan view of one of the manuals of the instrument, showing a strip of flexible material located, preferably though not necessarily, immediately in front of and slightly lower than the ordinary key-board of the instrument. This strip of flexible material is shown with the usual keys of an organ indicated therein, either by painting, or other suitable means. This flexible strip is composed of some insulating material which will effectively insulate it from the levers which are immediately below it and which are shown in Figs. 1 and 3.

Fig. 3 is a front elevational view, partly in section, showing a series of manually operable levers which are used to close the electrical circuits to one or more of the slide-operating electro-magnets. It also shows, in the lower part of the figure, a set of contact wires that are arranged in an inclined position and are embedded in a plate composed of suitable insulating material and so related to the curved end of the contact lever, that when more pressure is exerted on the flexible key-board, the curved end of the lever will successively engage wires which are electrically connected to electro-magnets which operate the bell-crank levers on the pipes for causing them to move toward the left.

Fig. 4 is a detail horizontal sectional view on an enlarged scale considered as taken on the line 4—4 of Fig. 1 showing the slides and the electro-magnets for operating the same.

Referring to the drawings in detail: Two of the adjacent pipes of an organ are indicated at 1 and 1' in a conventional manner and may be considered the "a" and #:a pipes in any octave. The electrically operated valves 2 in the wind chest 2' for controlling the flow of compressed air to each of the pipes are shown in a general way. It is to be understood that a chest 2' with valves therein is employed for each pipe. The ordinary keys of the organ are shown as a whole at 3; the white ones being shown at 4 and the black ones at 5.

Slidably mounted on the outside ends of the two pipes 1 and 1', indicated at 5² and 6 respectively, are slides. These slides, as shown, are operated by any suitable means, as by bell-crank levers 7 and 8 which can be moved by the series of electro-magnets 9, 10, 11, 12 and 13, five of which are shown for each slide. These magnets are individually located in the branch circuits 14, 14', 14², 14³, and 14⁴ which lead to a plurality of contact wires 15 that are fixed or embedded in the base piece of insulating material 16. It will be noticed that the wires 15 are arranged in an inclined direction, whereby the

curved and flexible contact fingers 17 which engage the wires 15 may successively close the circuits of the magnets as 13, 12, 11, 10, 9, depending upon the degree of pressure exerted by the player on the contact devices 70 as will be explained. 18 designates a plurality of pivotally-mounted levers that are arranged immediately under a strip of flexible and insulating material 19 which constitutes what may be termed a flexible key 75 board and these levers are operated by pressing downward and sliding the finger up or down the scale on the upper surface of this key-board. The above mentioned strip of flexible material extends the whole length of 80 the key-board of the instrument. It is situated immediately above and in contact with the manually operated contact closing levers 18. This strip of material has painted or otherwise indicated thereon, the usual keys 85 of the instrument as shown at 4' and 5'. Below each of these indicated keys there are shown five of the levers 18, each one of which is provided at its lower end with a curved flexible finger 17 already referred to. 90 These levers are pivotally connected with the instrument by means of a rod 20 which is insulated from the instrument. This rod has connected thereto a wire 21' that leads to one terminal of the battery 21. The connections to the terminals of the electro-magnets 9 to 13 of the first series and to the terminals 13' of the second series of electromagnets shown, it will be noticed, are in series with the other terminal of the battery 21 by 100 means of the wires 14², 15', 16', etc. The purpose of this arrangement is that when the operator slides his finger along or up or down the scale of the flexible key-board 19 exerting a downward pressure thereon, he 105 will energize in succession the different electro-magnets associated with each of the pipes and when the last magnet of one pipe is energized it will also cause the energization of the first magnet of the next pipe so that the bell crank 8 of that second pipe will be attracted toward the left hand end where one of the magnets 13' is located in order to be ready to take up the tone at the instant the preceding pipe stops. For instance, in 110 the drawing, Fig. 1, the levers 7 and 8 which control the slides 5² and 6 respectively will be in a position that the columns of vibrating air in the two organ pipes which produce 115 successive notes of the scale will be substantially the same length at the same moment, thereby producing a gradual loudness of sound from one pipe to the next. Furthermore, in order to increase the loudness of the tones it is necessary to increase the amount 120 of compressed air that enters the pipes. This is accomplished by means of the electro-magnetically operated valves shown at 2. These valves are operated simultaneously 125 with the slides 5² and 6. It is a well-known 130

fact that when the pressure of air in a pipe is increased it tends to raise the pitch of the tone. This throws the pipe out of tune with the rest of the instrument. In order, therefore, to be able to swell a single note in the organ some means must be provided whereby the slide on the pipe may be automatically lowered at the same time that more air is admitted to the pipe, in order to compensate for the natural raising of the pitch which is caused by the introduction of more air. This is accomplished by means of the curved flexible finger 17 at the lower end of the lever 18 engaging, in succession, the inclined contact wires 15. When the loudness of the tone is to be increased, the operator presses harder on the keys represented on the flexible finger board 19.

This causes the contact finger 17 to engage successively the different inclined contact wires 15, whereby the lever 7 will be attracted correspondingly toward the left thus lowering the slide 5² and lengthening the column of vibrating air in the pipe and compensating for the raising of the pitch of the tone through the simultaneous introduction of more air, by means of the valves 2 in the air chest 2', said valves being operated when the lever 18, by means of the arms 18' closes the circuits to the electro-magnets in the air chest 2. It is to be understood that the contact wires 15 may be placed in a horizontal or other suitable position but it is less troublesome as far as mechanical or structural details are concerned to arrange them, as shown, in an inclined position. It is for this purpose that the contact wires 15 are set in an inclined position, so that increased pressure on the key represented on the flexible strip 19 at 4' and 5' will cause the finger 17 to operate by flexure, and engage successively the wires 15 to cause the energization of electro-magnets to the left thus lowering the slide 5 and compensating for the increased air pressure as above stated. It is to be understood that when the operator places his finger on the strip of flexible fabric 19, at the point 5', he can operate several of the levers 18, and thus simultaneously close the circuit to the several contact fingers 17, whereby several of the valve operating electro-magnets as 10, 11 and 12 are energized. As the operator slides his finger along the flexible strip 19 the corresponding levers 18 will be successively operated thus causing the bell crank 7 to swing to the right or left in a gradual manner, meanwhile the other arms 18' of the levers 18, according to the degree of pressure on the key board 19, are closing the contacts at 20' to the wind chest 2 to supply compressed air to the pipe under operation. It is to be understood that the normal position of the levers 7 and 8 is vertical and that the same are moved either

to the right or left depending upon which of the magnets are energized. The slide 5² is moved so as to automatically maintain the length of the column of vibrating air practically constant.

If the operator desires to make a louder tone, he can do so by increased pressure on the key board, for this will successively close the contacts 20', thus increasing the pressure in the pipe, but in swelling a single tone the natural raising of the pitch through increased air pressure would naturally throw the pipe out of tune and to compensate for this and keep the pitch constant in spite of the increased loudness, the slides 5² and 6 are simultaneously lowered, which will lengthen the column of air in the pipe, thus lowering the pitch just as much as the extra air pressure would raise it, thus securing an equilibrium of pitch.

What I claim is:

1. In a pipe organ, the combination with the pipes of the same of a slide for each pipe for varying the length of the vibrating column of air therein, electro-magnets for controlling the operation of the slides, a source of electric energy, connections between the source of electric energy and the electro-magnets, a plurality of circuit closing wires, contact fingers to engage one or more of said wires to close one or more of the connections to said magnets to cause the slides to be shifted for producing a tone gradually varying in pitch in the pipes and from one pipe to the next, as set forth.

2. In a musical instrument of the kind described, the combination with the pipes and key board of the same, of a plurality of manually operable devices and electro-magnetic means controlled by the devices for controlling the lengths of the columns of vibrating air in the pipes, as described, in a uniformly or gradually varying manner.

3. In a pipe organ the combination with the pipes thereof, of a slide for each pipe for varying the length of the column of vibrating air, electro-magnetic devices for moving the slides, and electro-magnetic devices for controlling the supply of compressed air to each of the pipes and operated simultaneously with the movement of the slides, manually operated contact means electrically connected to said devices and located adjacent to the key-board for causing the energization of both of the said electro-magnetic devices, the electro-magnetic devices of adjacent pipes which produce successive notes of the scale being simultaneously energized to cause the tones of the adjacent pipes to be substantially of the same pitch for the purpose described.

4. In a pipe organ, the combination with the pipes thereof, of a slide for each pipe for varying the length of the column of vibrating air therein, electric contact de-

vices, a plurality of electro-magnets for operating the slides, electrical connections between the contact devices and the electro-magnets, means for closing the contact devices of said electro-magnets to change the position of the slides, valve devices for varying the air pressure in the pipes, which latter devices are operated simultaneously with said contact devices that close the circuits to the electro-magnets for the purpose described.

5. The combination with the pipes of an organ, of electro-magnetic means for varying the lengths of the columns of vibrating air therein, including slides and electro-magnets connected to shift them; means to supply compressed air to the pipes, valves for controlling the air, manually operated means to cause the operation of said electro-magnetic means and the simultaneous operation of the valves to vary the supply of compressed air to the pipes.

6. A pipe organ having, in combination with the pipes thereof, a slide on each pipe for varying the pitch by changing the length of the column of vibrating air therein, means including electro-magnetically operated valves and electric connections therefrom for varying the supply and air pressure in the pipes, electro-magnetic means for operating the slides including a plurality of manually operable electric contact levers for each note of the instrument, flexible contact fingers carried by the levers, a plurality of circuit closing contact wires spaced from each other and engaged by the flexible contact fingers, said levers also serving to simultaneously close the electric connections to the valves for varying the supply of air to the pipes, whereby upon increased manual pressure being applied on the levers, the air supply and the length of the column of air in the pipes will be varied by operating the slides on the pipes through the electric connections to the electro-magnetically operated valves and slides, thus compensating for the natural rising of the pitch through the increased air pressure.

50 7. A pipe organ having devices for varying the lengths of the columns of air in the pipes thereof, electro-magnets for operating the devices, a plurality of contact levers each lever having a contact finger for clos-

ing the circuits to said magnets a plurality of inclined contact strips with which the fingers engage to close successively the circuits to said magnets, whereby the slide devices are movable at a uniform rate of motion for the purpose of gradually varying the pitch of the tones of the pipes.

8. The combination in a pipe organ, of pipes, a slide for each pipe, electro-magnetic means for operating the slides, electric contacts under the control of the operator for operating said slide operating means and additional electro-magnetic means for simultaneously controlling the supply of compressed air to the pipes as the slides are operated, for the purpose of changing the tones of the pipes, either for raising or lowering the same, said slides serving to compensate for the raising of the pitch of the note through increased air pressure by simultaneously lengthening the column of air in the pipe.

9. In a pipe organ, the combination, of pipes, a slide for each pipe for varying the column of vibrating air therein, electro-magnets for operating the slide of each pipe, contacts, connections from the contacts to the electro-magnets, and including a source of electric energy, flexible fingers in the connections and means for comprising a flexible strip for operating the fingers when pressure is applied to said strip.

10. In a pipe organ, the combination, of pipes, means for varying the length of the column of vibrating air in each pipe, electro-magnets for operating said means, electro-magnetic means for varying the air pressure in the pipes, two sets of electric contacts, connections from the respective contacts to said electro-magnets, a source of energy in the connections, means for simultaneously closing the two sets of contacts and a flexible strip engaging the contact closing means to operate the contact closing means when pressure is applied thereto, said contact closing means being so constructed as to cause a progressive or step by step movement of the means for varying the length of the column of vibrating air in the pipes and variation of the air pressure therein as the length of the column is varied.

HOMER B. HULBERT.
